UNITED STATES PATENT OFFICE

SAMUEL F. STEIN, OF WILLIAMSPORT, PENNSYLVANIA

APPARATUS FOR ELECTRICAL TRANSMISSION OF INTELLIGENCE

Application filed June 29, 1927. Serial No. 202,376.

My invention relates to the utilization of both wired and wireless telephone systems for transmitting sounds emitted or produced by phonographic apparatus, and, broadly considered, it has to do with the automatic control of the connection of such apparatus with the subscribers' circuits, and, in its narrowest aspect, it has to do with the utilization of the telephone system and the phonographic apparatus for advertising purposes.

In the annexed drawings.

Fig. 1, is a view diagrammatic in nature, illustrating an embodiment of my invention;

Fig. 2 is a detail view showing a preferred construction of phonographic record feed mechanism;

Fig. 3 is a section on line 3—3 of Fig. 2;

Fig. 4 is an end elevation showing the record driving mechanism;

Fig. 5 is a view similar to Fig. 1 illustrating the application of radio to my invention;

Figs. 6 and 7 are detail views of a time switch that may be used therewith.

In producing my invention I have aimed to satisfy, and to utilize for advertising purposes, the desire of many people to ask the time of the day of the operators at telephone exchanges, which now is prohibited because of the burden of extra work the response of

the operators to such inquiries places upon them and without compensation to the telephone company for the service thereby rendered. To this end, my invention, as shown in Fig. 1, briefly described, contemplates the

employment of a phonograph with a record that contains announcements of the time for every minute, or other regular interval say for twelve hours, and a second phonograph with a record containing the advertisement which may be merely the name of the advertiser, and timed to call the name in the intervals between the time announcements, and these two phonographs being situated so that the calls they emit will be received by a conveniently located transmitter on a telephone line leading to the switch board. This line may be given a number or a verbal designation as for example, the word "time", so that a subscriber, desiring to learn the hour, will signal central in the usual way, calling for

"time", whereupon the connection will be made between his line and the phonograph line and the phonographs will telephone, say, "John Wanamaker, nine thirty". The phonographs will, of course, run continuously during the day, but no one will hear their periodical calls unless the lines are connected at central. By prefacing the call of the hour with the name of a person or concern, the latter will appear to be answering the inquiry, and thus an advertising medium is provided, profitable both to the telephone company and subscriber. By having a separate record for the advertiser's name, the records can be changed from time to time, to change names, without the necessity of making a new record for the time announcements, so that one of the time announcing records will serve for a great number of name records. Referring to the drawings, 10, designates the phonograph with the time announcing record; 11, the phonograph with the name record, the two being geared together to the same driving shaft S, so that they will run in proper time relation; 12, the transmitter adjacent but with no means to connect with the phonographs; 13 the switch board at central, and 14 the receiver of a calling subscriber.

I prefer the stylus of each phonograph normally out of contact with its record and automatically placed in contact therewith only when there is a call for time, and thereby needless wear of the needles and record may be avoided so that they may be used without change for a practically indefinite time. This may be accomplished in various ways. Thus the tone arm 15 of the phonograph may be pivoted to the frame so that normally the needles of the sound box 16 is kept lifted above the record 17 (which in the machine shown in the drawing is a cylinder) and by an electromagnet 18 is moved to place the needles in the record groove, when the plug P is inserted in the jack J by the switch board operator, said magnet 18, being in a circuit that has a switch 19 that is closed on the insertion of the plug and remains closed until the plug is withdrawn. The magnet armature 20 is connected by a spring 21 with the tone arm, so that though the armature

remains fixedly held by the magnet attraction, the tone arm is yieldingly held and hence a rigid contact of needle and record is avoided, and the needle gently and yieldingly is held in the record groove in the cylinder. 5 The tone arm, of course, travels along the direction of the length of the cylinder so that when the needle is brought in contact with the cylinder, it accurately engages the record groove at the proper point to give the correct 10 time, in the one case, and the name, in the other case. A screw 22 is provided to cause the lengthwise travel of the tone arm (and with it the magnet and armature) the carriage 23 being provided with a pin 24 that engages 15 the thread. Said pin 24 is movable into and out of the thread groove, and it is automatically moved out of the groove at the end of the travel, by engaging a cam surface 20 at the end of the screw thread. When the pin 24 is thus lifted out of the thread groove, the carriage, sliding on rods 23a is automatically returned to its starting point by the action of a spring or a weight W, against the 25 pull of which the screw feeds the carriage. A spring actuated latch, 26, engages the shoulder 27 on the pin and holds the pin out of contact with the thread during the return movement, and when the latter is completed, 30 the latch strikes a projection 28 and is moved to release the pin, which thereupon drops into working engagement with the screw. It is not necessary that the needle for the name record travel, because that record can be a 35 single circular path and not a spiral.

Inasmuch as the phonograph is connected with a calling subscriber, at central, precisely as a personal subscriber is, which is by the ordinary use of the switchboard upon a 40 call to central, and as such call might be made during the return travel of the needle or stylus to the starting point of the record, it is important to prevent the dropping of the stylus or needle into contact with the record, 45 during such return travel, for then the needle would injuriously scrape over the record. I, therefore, provide means for preventing this, which may be given various forms. I prefer an automatic device for this purpose, and 50 one which is actuated by, or is under the control of the phonograph, and which, in the embodiment of my invention illustrated in the drawings, will cause the circuit that includes the magnet 18 to be broken during the 55 period of the return travel of the needle, and closed during the time of the forward travel of the needle. Describing now, in detail, the particular control device shown, it includes a switch 29 in the circuit of the magnet 18, 60 which is preferably the telephone circuit, which is of the form having two sliding buttons 30 and 31 that protrude from the switch box on the opposite sides thereof, so that the button 30 is in position to be engaged by 65 the carriage 23 just when the latter about

completes its forward travel, or carries the needle to the record, and thereby the switch is operated and the magnet circuit is broken. The other button 31 is in position to be struck and moved by a lever 32 which is connected 70 by a rod 33 with a lever 34 pivoted near or at the point where the carriage 23 starts on its forward travel over the record, so that on returning to such point the carriage 23 will strike and move the lever 34 and through the 75 link rod 33 will rock the lever 32 in the direction to cause it to engage and move the button 31 and thereby operate the switch 29 to close the magnet circuit and place all in readiness for the automatic placing of the 80 needle into contact with the record when a subscriber calls and in response thereto, the phonograph circuit is plugged with that of such calling subscriber.

Of course, by suitable gearing the record 85 and the feed screw are driven at the proper speed, which will be relatively fast for the record and relatively slow for the feed screw, and as this will result in differential travel of stylus or needle and screw engaging pin 24, 90 which would cause twisting and binding, I, momentarily, disengage the needle from the record groove at each revolution of the record, when a cylinder. This may be done by resting the tone arm 15 upon a rod 35 95 parallel with the cylinder axis that is pivoted at its ends to the phonograph frame 36 and having a radial finger 37 in the path of a cam tooth 38 at the end of the cylinder, which, by the revolution of the latter, acts on the finger 37 and rocks the bar 35 upward and thereby the tone arm is swung upward and lifts the needle from the record. Being thus freed from the record, any lateral pressure due to the differential travel of record and feed screw will be relieved, and, as soon as the tooth 38 passes the finger 37, the needle at once drops into engagement with the record groove at a point with which it alines. To 100 allow slight lateral motion of the tone arm for the proper adaptation of the needle to the record groove, I may place a spring between the side of the tone arm and one or both of the adjacent uprights 39 in holes in which the tone arm pivoting pin 40 is 105 mounted.

Since, by my invention, the phonograph means may have a circuit that corresponds to a personal subscriber's circuit such means can be located at the place of business of the 110 subscriber arranging for the service, if desired, so that it is wholly under his own control.

I do not limit myself to the cylinder or to any particular type of phonograph or sound 115 reproducing mechanism; to the details of construction I have shown and described.

To reduce friction and save wear the portion of the pin, 24, acting in the groove may be provided with an anti-friction device such

as a ball or roller to touch the groove sides and bottom or with oil supplying means.

My invention is applicable to automatic telephone systems as well as manual systems and it is within its scope, and in both systems, to make provision for enabling several subscribers to be connected at the same time, with the phonograph circuit, so that one will not have to wait for another, especially when the "talk", in addition to giving the time, is of any length. Thus, as shown in Fig. 1 there may be several, independent transmitters, 12. As there is no connecting means between phonograph reproducer and phone transmitter this separated transmitter arrangement may be used; and, of course, each such phone may be put to the ordinary use without any inconvenience to the talker.

I also contemplate the radio transmission of the matter on the time and name records, see Fig. 5. To do this the sounds from the respective phonographs will be delivered to a microphone at a broadcasting station, and, of course, the time-of-day and the other matter will be received at all radio receivers that are tuned in with that station. And by keeping the receivers tuned in they become the equivalent of a clock in constantly denoting the time, with the difference from an ordinary clock, that the time is announced verbally, and to the ear instead of to the eye. By using a clock at the broadcasting station which has chimes, the sound of the chimes may be given directly to the microphone, and be either supplementary to the phonograph announcement, or as a thing separate or independent.

The transmitting apparatus at the broadcasting station may consist of a time mechanism, C, see Figs. 6 and 7, two phonograph mechanisms, each with its own stylus, 160, the time mechanism operating a switch with contacts that, respectively control the step-by-step rotation of the phonograph records, 170, and close the circuits through the stylus operating magnets, 180, to place these at the minute intervals in contact with their respective records and hold them long enough to cause the time and the other matter to be uttered into the microphone, 120, and thence, transmitted to a distant receiver, 140, equipped, as usual with phone head set and loud speaker connections. A good arrangement with both the head set and loud speaker when the clock has chimes, is to provide a time switch, 41, in the loud speaker connection which will connect the loud speaker in circuit only at the chime intervals, so that the announcement of the time will be heard only through the head set. However, by a shunt having a switch, 42, the time switch, 41, may be cut out, and the loud speaker connected, so that it will give every time announcement including the chimes that is broadcasted. An excellent time switch mechanism for the apparatus is shown somewhat

diagrammatically in Figs. 6 and 7. Geared to and driven from the clock, C, by connections not necessary to be described, are four rotary discs, each with a peripheral contact for closing and opening the desired circuit, the disc, 43, controlling the circuit to the magnet, 180, of the time-announcing record; the disc, 44, controlling the circuit to the magnet, 180, that controls the stylus of the advertiser record; the disc, 45, controlling the circuit of the devices for the step-by-step rotation of the feed device for the time announcer, and the disc, 46, controlling the circuit for the step-by-step rotation of the feed device of the advertiser. The circuit which is controlled by the switch, 45, includes a solenoid, 47, the core, 48, of which is engaged by a lever, 49, having between its ends a fulcrum or pivot, 50, and which carries a pawl, 51, adapted to engage one at a time, the ratchet teeth of a wheel, 52, which is fixed to the shaft of the rotary feed screw, 53, of the time announcer like the screw, 22. When the circuit is closed through the solenoid, 47, by the switch disc, 45, the following movement of the core, 48, will rock the lever, 49, on its pivot, 50, and the pawl, 51, engage a tooth of the ratchet wheel, 52, the latter will be rotated the desired extent and upon the breaking of the circuit by the switch disc, 45, the lever, 49, will be pulled in the opposite direction by a coil spring, 54, to retract the pawl, 51, for engagement with a fresh tooth, the pawl, 51, tripping over the adjacent ratchet tooth. To change the stroke of the lever, 49, for adjustment purposes, the fulcrum, 56, is carried by an adjustable plate, 55. Preferably the core, 48, has an anti-friction roller, 56, to bear against the lever, 49. The lever, 49, preferably has a handle, 57, by which it may be rocked by hand to rotate the feed screw, 53, should that be necessary for timing purposes. That adjustment can only be forward, and as backward adjustment may be necessary, the ratchet wheel, 52, may have a handle, 58, for turning the feed screw, 53, backward as well as forward. For backward movement, the pawl, 51, must be lifted from engagement with the ratchet wheel, 52. The circuit controlled by the switch disc, 45, includes mechanism precisely like that just described or imparting step-by-step rotation to the feed device of the advertiser, but it has not been considered necessary to repeat the illustration in the drawing.

Preferably the circuit controlled by the switch disc, 46, has a hand switch, 59, to enable the advertiser feed mechanism at will to be placed out of operation. This enables the repetition as long as desired of the same advertisement. It is also of advantage in changing the time relation of the time announcer and the advertiser, so that on different days, for example, the time of day when

announced may have associated with it the names of different advertisers. As one of the advantageous uses to which apparatus embodying my invention may be put in order to secure the greatest possible benefit and return from the advertisements, is to offer prizes to listeners-in, who will send a written report to the advertisers of the time and the subject matter of a particular advertisement, it is desirable to vary the relation of time and subject matter announced, so that a listener-in cannot determine in advance and thus render a report not on the basis of what he has actually heard, but on what he has worked out, the time relation of announced time and advertisement, that object can be achieved by the use of the switch, 59. Such object may also be achieved by making the advertising record shorter or longer than the time record, which would result in the displacement of any definite time relation between time announced and advertisement, and to prevent a listener-in taking advantage of the discovery of any regularity of cycle in that arrangement, it may be supplemented by the use of the switch, 59, so that there will be two factors to prevent any such systematic rendition of time and advertisement that could be taken advantage of by a listener-in. Although there will probably be no occasion to interrupt the announcer of time from the time record, yet I prefer to provide a switch, 590, in the solenoid circuit that is controlled by the switch disc, 45, to enable that circuit to be opened and closed at will.

An important advantage of disengaging the stylus from the record when the record has a spiral groove is that by the disengagement of the stylus from the record spiral, the possibility of accurate repetition of the same part of the record is assured, for the stylus, of course, will be returned to the beginning point of the part of the record which is to be repeated. The record groove, of course, need not be a helix or a spiral, but can be a succession of side-by-side complete circles, this last named arrangement being desirable when repetition is desired. When repetition is not desired, the stylus will be lifted from the circular groove to allow shifting to the next groove.

In those cases where persons desire to have the time announcing service, but have no radio receiver, but do have a telephone, the telephone exchange serving such a person will be equipped with a radio receiver that will receive the time announcements from a central broadcasting station, and by phone connection, with the apparatus shown in Fig. 1, such a subscriber will receive the time announced along with the advertising matter; or the exchange can make connections between a subscriber having no radio receiver and some other subscriber or station having a radio receiver, and a constantly open telephone trans-

mitter, which will transmit messages or sounds to any other telephone subscriber connected therewith. It will be seen that by the use of radio, very great simplification of apparatus is possible for wide-spread of universal transmission of time and advertising matter therewith.

Preferably each phonograph mechanism, as shown in Fig. 5, is equipped with a switch, 290, corresponding to the switch, 29, of Figs. 1 and 2.

While I have described the transmission of clock chimes directly from the chimes of the clock, it, of course, will be understood that the phonograph record may contain the chimes as well as verbal announcement of intervals of time.

What I claim is:

The combination of plural sound producing means including separable records and their respective coacting members for sound production adapted independently to produce sounds, one of said records being adapted for announcing the time and the other record for announcing other matter alternately with the time announcement, automatic means for repeatedly placing record and its respective coacting member into and out of coacting relation at different points of the record before the completion of travel of said coacting member over the record, and automatic means for changing the point of coaction at regular time intervals.

In testimony whereof I hereunto affix my signature.

SAMUEL F. STEIN.
